AUTOMATIC TELEPHONE SYSTEM

Erik Waldemar Hullegård, Stockholm, Sweden,
assignor to Telefonaktiebolaget L. M. Ericsson,
Stockholm, Sweden, a company of Sweden

Application November 9, 1937, Serial No. 173,697
In Sweden November 14, 1936

3 Claims. (Cl. 179—16)

The present invention relates to automatic telephone systems and has for its object to provide an arrangement in such systems rendering possible the automatic setting up of telephone connections between different lines over electronic or discharge paths, for example connections from subscriber's lines to link lines within a telephone exchange or vice versa. According to the invention said object is attained substantially by connecting each wire of a calling line over a resistance to a source of current having a voltage which differs from the voltage of the corresponding wire in the called lines.

The invention is described more in detail having reference to the drawing attached to this specification and forming part thereof, which drawing shows as an example an application of the invention in an automatic telephone exchange.

A subscriber A_1 is connected to the exchange over a two-wire line AL_1 and AL_2 . In the exchange each wire of the line is connected in multiple to electrodes 1 of a number of discharge paths or tubes U_1 and U_2 , the other electrodes 2 of which are connected to a two-wire link line FL_1 and FL_2 within the exchange. According to the invention each one of the two branches of the subscriber's line is also connected at a point 5 or 6 respectively over a resistance r_1 or r_2 respectively to the plus-pole or minus-pole respectively of a battery E_1 . In each branch a resistance r_3 or r_4 , which is connected in parallel with a condenser C_1 or C_2 , is included between the electrode 1 and the connecting point 5 and 6 for the battery. The two branches of the link line are connected over resistances r_5 and r_6 to the plus-pole and minus-pole respectively of a second battery E_2 . The voltage of the battery E_2 differs from the voltage of the battery E_1 . The voltage difference of the two batteries is so determined that it does not cause ignition of the discharge paths. Between the two electrodes 1 and 2 there is provided in each discharge path a marking line ML , grid 3 which is connected to a marking line ML .

The switching operations taking place upon a call from the subscriber's set A_1 will first be described. When the subscriber A_1 lifts off his micro-telephone, a circuit is closed over the subscriber's set, the subscriber's line AL_1 , AL_2 , and the resistances r_1 and r_2 . In case the resistance of the subscriber's line should not be of the proper magnitude, a resistance connected in parallel with a condenser can be included also between the subscriber's set and each one of the connecting points 5 and 6 . The current passing

through the resistance r_1 causes a drop of voltage resulting in a reduction in potential at the point 5 where the battery E_1 is connected to the subscriber's line AL_1 . The resistance r_1 is so dimensioned that said reduction of voltage will be sufficient to increase the voltage difference between the subscriber's line AL_1 and the link line FL_1 to the ignition voltage for a discharge path U_1 . Since the two branches of the subscriber's line are connected in multiple with a plurality of pairs of discharge paths special provisions must be made to insure connection between the other branch AL_2 of the subscriber's line and the branch FL_2 of the same link line. For this purpose, discharge paths having different ignition voltages can be provided, for example, in the same sequence for both branches of the different subscriber's lines. Alternately, the ignition of one discharge path U_1 can be made to cause ignition of the corresponding discharge path U_2 , in that for example provisions can be made to ensure that the voltage E_2 is applied on the corresponding link line branch only after the path U_1 has been ignited and the line FL_1 energized. Ignition of both paths U_1 and U_2 completes the connection between the subscriber's line and a link line in the exchange. The current now set up changes the potential of the wire so that no other subscriber's line can be connected to the same link line, the current through the resistance r_2 raising the voltage of the electrode 1 and of the electrodes connected in multiple therewith to such a degree that none of the discharge paths to which said latter electrodes appertain can be ignited. The same current causes also in the resistance r_5 a voltage drop which lowers the voltage of the electrode 2 and of the electrodes connected in multiple therewith to such a value that no other discharge path appertaining to the link line FL_1 can be ignited. Busy marking is thus effected immediately.

The switching operations taking place upon a call intended for a subscriber A_1 are the following. A register or other switching device actuated upon a call from a subscriber by the numerical impulses marks in ordinary manner over lines ML the pair of discharge paths U_1 and U_2 which connect the calling link line with the desired subscriber's line. Over the marking lines ML the potential on the grids 3 of the discharge paths is changed so that said paths are ignited. Said marking occurs only during a brief moment. A ringing signal can be transmitted to the subscriber A_1 by generating oscillations in the tubes U_1 and U_2 , for example in cooperation with con-

densers and resistances, or by connecting a suitable ringing current source to the link line. A connection can also be set up from a link line to a subscriber's line by changing the potential 5 on the branches of the link line and by simultaneously changing the grid potential in the corresponding discharge paths. The ignition of the discharge paths is then brought about through 10 co-operation between said two changes of potential.

I claim:

1. A telephone exchange comprising, link lines at said exchange and subscriber lines connected to said exchange, discharge paths arranged between the corresponding speaking wires of said link lines and subscriber lines, a current source of certain voltage connected to each speaking wire of a subscriber line over resistances, a second current source of another voltage connected to each wire of the link lines, the voltage difference between said current sources being so determined that an increase of said voltage difference will cause ignition of the discharge paths to provide a direct connection between a link line and a subscriber line over said discharge paths, a resistance and a condenser arranged in parallel in each branch of a subscriber line between electrodes of the discharge paths and the points on the line in which the current source is connected.
2. A telephone exchange comprising, link lines at said exchange and subscriber lines connected to said exchange, discharge paths arranged between the corresponding speaking wires of said

link lines and subscriber lines, a current source of certain voltage connected to each speaking wire of a subscriber line over resistances, a second current source of another voltage connected to each wire of the link lines, the voltage difference between said current sources being so determined that an increase of said voltage difference will cause ignition of the discharge paths to provide a direct connection between a link line and a subscriber line over said discharge paths, a grid 10 in each discharge path, means for simultaneously changing the potential on the branches of the link line and the potential of the grids belonging to the discharge paths between said link line and a subscriber's line whereby the discharge 15 paths are ignited upon a call from said link line to said subscriber line.

3. A telephone exchange comprising, link lines at said exchange and subscriber lines connected to said exchange, discharge paths arranged between the corresponding speaking wires of said link lines and subscriber lines, a current source of certain voltage connected to each speaking wire of a subscriber line over resistances, a second current source of another voltage connected to each wire of the link lines, and the voltage difference between said current sources being so determined that an increase of said voltage difference will cause ignition of the discharge paths to provide a direct connection between a link line 30 and a subscriber line over said discharge paths.

ERIK WALDEMAR HULLEGÅRD.
